WINDOW SASH CONTROL

Filed Oct. 31, 1945

UNITED STATES PATENT OFFICE

2,503,076

WINDOW SASH CONTROL

Harold J. Smith, Brooklyn, N. Y.

Application October 31, 1945, Serial No. 625,717

1 Claim. (Cl. 292—75)

1

My invention relates to window sash controls and more particularly to ball bearing supported window sashes for facilitating the movement of the sash within the frame.

Many patents have been issued for similar devices but it is doubtful if any have gone into commercial use. It is the primary purpose of this invention, therefore, to provide a device of the foregoing character, which is sufficiently simple in construction, easy to install and operate, and inexpensive in cost, to warrant its general acceptance by architects and contractors.

Other objects are to provide a substantially frictionless device that is adjustable with respect to the window frame; that may be made self-adjusting with respect thereto; which may be combined with a novel form of weather-stripping, running the length of the window frame; which requires less effort when installed in a window sash for operating the sash from one position to another; and which will permit the window to be raised to any desired position and be securely held thereon.

I accomplish these and other objects and obtain my new results as will be apparent from the device described in the following specification, particularly pointed out in the claim, and illustrated in the accompanying drawing in which:

Fig. 1 is a front elevation of a window frame and sash employing my invention, and shown partly in section.

Fig. 2 is a transverse sectional view taken through the plane 2—2 of Fig. 1.

Fig. 3 is a detailed view of one end of a window sash shown in Fig. 2.

Fig. 4 is a perspective view of a ball bearing socket device forming a part of my invention.

Fig. 5 is a perspective view of a section of the weather-stripping employed in my invention.

Fig. 6 is a detailed sectional view of one end of a window sash shown in Fig. 2, illustrating a self-adjusting modification of the ball bearing socket device.

In the drawing, reference numeral 10 designates a typical window frame, employing upper and lower window sashes 11 and 12, respectively, operating in the grooves 13 and 14 between the parting beads 15 mounted on the side jambs 16 and the stops 17 and 18.

On both edge faces of side portions 19 of the window sashes which ride in the grooves and at appropriate points, at least two ball-bearing socket devices 20 are mounted in recesses 21 therein. In the drawing, they are shown at the top

and bottom of each window sash. They may be placed at intermediate points additionally.

Each socket device contains a spring actuated ball-bearing 22 projecting partially therefrom, which rides on the corrugated strip 23 longitudinally positioned in the groove. The strips are provided with a plurality of continuously connected camming sections or corrugations, preferably curved, which furnish seats for the ball bearings, the seats having preferably a radius of curvature slightly less than the radius of the ball bearings, so that the ball bearings may be seated firmly in the corrugations, as shown in Fig. 6, but which may conveniently be cammed therefrom. Thus the sash will be securely positioned when the balls are seated on the corrugations and there will be no likelihood of rattling or other motion, unless the sash is manually moved therefrom.

20. The ball-bearing socket device 20 and corrugated strip 23 are shown in section in Fig. 3, wherein the ball-bearing 22 is seated in an aperture 24 located in the front section 25 of the tubular socket 26, with a suitable spring 27 contained therein. The spring rests on the back wall 28 of the socket and operates against the back side of the ball, urging it into the seat formed by the aperture. The socket 26 may be force-fitted into the drilled hole 21 of the window sash and the shoulder 29 on the front section will seat itself on the recessed face 30 of the side member 19 of the window sash, establishing a fixed outward position of the ball with respect thereto.

35. In Fig. 4, the ball-bearing socket device is shown provided with a front section 31, having a plurality of counter-sunk screw holes 32 for enabling the device to be attached by screws to the wall 30, eliminating the need for force-fitting the socket in the drilled hole 21.

40. In Fig. 6, a modification of the socket device is shown, which permits an automatic outward adjustment of the ball bearing with respect to the socket device, to compensate for unevenness in the window frame, and for any wear that may occur in the corrugated strip that is greater than the distance the ball can be normally projected from the fixed front plate of the socket device.

45. Here the ball is seated in a cup-shaped member 33 having a seating aperture 34 in the bottom of the cup, for the ball. The spring 35 is contained within the cup, one end of the spring operating on the ball, with the remaining end of the spring pressing against the end wall 37

50. 55. of the tubular sleeve 36 which is seated in the

drilled hole 21 on the face 30 of the side portions 19 of the window sash. The cup-shaped member 33 has a diameter permitting an easy slide-fit within the tubular sleeve, so that the ball and cup-shaped member are adjustably mounted with respect to the side face 30 of the sash. This permits the ball to be properly seated at all times while under pressure of the spring, even if the distance between the strip 23 and the surface 30 is greater than expected. A pin 36a 10 may be mounted in the side wall of sleeve 36, and extend into a slot 33a in the side of the cup-shaped member to keep the parts together, the length of the slot providing for the maximum distance member 33 may be projected. The sleeve 36 may 15 be force-fitted in the hole 21 or provided with a front lip 38 having apertures 39 for screws 40 which may be used to secure the sleeve 36 to the window sash.

The corrugated strip 23 may be provided with an uncorrugated flange 41 slidably fitting into groove 42 extending longitudinally on the face 30 in the side portions 19 of the window sash. Thus a weather-stripping feature may be added to the corrugated strip if desired. It is desirable to position the flange 41 between the outside of the window and the ball-bearing devices for protecting the same from the weathering elements. The strips are fastened to the side jambs by small nails or screws 43, preferably alternately positioned on each side of the corrugated section on the strip 23, as shown in Fig. 5. The strip may be moulded into the form shown in Fig. 5, or one of the legs of a right-angle section may be pressed from the flat to corrugated shape by passing it through a pressing roller. The strip itself may be made of metal or suitable plastic that will not unduly wear under the action of the rolling ball bearings.

It will be helpful in the operation of the invention if the strips on each side of each window sash be matched to the position of their associated ball-bearing devices, so that when one ball is seated in one corrugated strip, the remaining balls will be similarly seated in the remaining positions on each sash.

By employing the combination of ball-bearing supporting devices with corrugated strips, I have obtained the principal object of my invention. By the use of self-adjusting ball-bearing supporting devices, I am able to provide for variations in dimensions that are greater than can be expected from the distances each ball-bearing pro-

jects from its associated mechanism. The combination of a corrugated strip with a weather-stripping flange enables me to provide a window sash and frame designed to exclude the weathering elements from the ball-bearing devices, thereby protecting them.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claim, and by means of which, objects of my invention are attained and new results accomplished, as it is obvious that the particular embodiments herein shown and described are only some of the many that can be employed to attain these objects and accomplish these results.

I claim:

In a window frame and sash construction wherein the sash has two side portions each provided with a plurality of holes and the frame is provided with grooves for slidably moving the side portions of the sash therein, a sash holding device adapted to cooperate with a corrugated strip mounted within the grooves, said device comprising a socket member mounted within each hole, a spring mounted within the socket member, a front section longitudinally slidably in the socket member and having an apertured seat, and a ball-bearing seated in said aperture and urged into the seat by said spring, whereby the window sash will be supported by said ball-bearings engaging the surfaces of the corrugated strip.

HAROLD J. SMITH.
